UNITED STATES PATENT OFFICE

WILLIAM A. ADAMS, OF BROOKLYN, NEW YORK

DISPLAY DEVICE

Application filed August 13, 1931. Serial No. 556,782.

This invention relates to display devices, and my improvements are directed to means for producing upon a translucent shade, grotesque formations and sinuous movements 5 of figures that are projected thereon, by a source of light, from a rotating support for such figures. For example, if swimming fish are represented on a cylindrical, rotating transparency, and are projected by light upon 10 the shade, it is intended by me that, due to a certain angular configuration of said shade, the effect to the observer will be that the fish are rising and falling in their travel movements and also that the outlines of their 15 forms vary in an amusing manner.

Similar effects are obtainable when the objects pictorially represented on the transparency are hounds chasing a quarry, huntsmen, ocean waves, or other objects capable of 20 motion.

In obtaining this new motion effect for a projected pictorial representation I employ a shade that is composed of a suitable translucent material, such for example as ground 25 or frosted glass, making said shade polygonal in cross-section, with its sides concavo-convex, and having its points of intersection rounded or blunt, said shade having in cross-section or plan view generally the appearance 30 of a star whose points are rounded off.

As the transparent cylinder, which may be of cellophane or other suitable material, rotates within this angled shade, the figures projected from the cylinder on the interior 35 of said shade appear to the observer to be enlarged as they pass the rounded points of intersection, and attenuated as they pass the concavo-convex sides, thereby also providing the further effect of rising and falling as 40 these figures pass in review.

Other features and advantages of my invention will hereinafter appear.

In the drawing:

Figure 1 is a side sectional elevation of a 45 device embodying the features of my invention.

Fig. 2 is a horizontal section thereof, taken on the line 2-2 of Fig. 1.

Fig. 3 is a plan of the base or support, and 50 Fig. 4 is an enlarged view of the trans-

parent cylinder, the surface thereof bearing the imprint of figures, for projection.

In said views let 1 indicate a base or stand, which is provided with a central orifice 2 that is adapted to receive the mount 3 for an upwardly extending electric light bulb 4. 55

A hollow, transparent cylinder 5 surrounds the bulb 4 and is provided with a top 6, having a series of vanes 7 cut therein, said top also having a central bearing 8 in its under 60 surface for support upon the rounded end of an angled rod 9 that is here shown as engaged, at its lower end, with the mount 3.

It is intended that heat waves from the bulb 4, coacting with the vanes 7, will serve 65 to rotate the cylinder 5.

The base 1 is provided in its upper surface with an angular groove or recess 10 which extends in somewhat the configuration of a star, and a vertical shade 11, composed of translucent material, and whose cross-sectional contour corresponds with the contour of groove 10, is adapted to be seated in said groove, whereby said shade will surround the 70 cylinder 5.

As has been premised the polygonal sides of the shade 11, here indicated at 12, are of concavo-convex contour in cross-section, and at their points of intersection, blunt or rounded connecting formations 13 are provided. 75

It is by means of these particular contours 12, 13 in the polygonal shade that the figures 14 on the rotating cylinder 5, here represented for example as fish, and projected by the 80 light from the bulb upon the shade, appear to the observer as constantly varying in their shapes, and as rising and falling in their travel motion.

The cable connection to the lamp is indicated at 15, and may be provided with a switch 16 located in a hole 17 provided therefor in the base. 85

Variations within the spirit and scope of my invention are equally comprehended by 90 the foregoing disclosure.

I claim:

1. The combination with a lamp of a transparent, hollow cylinder surrounding said lamp, said cylinder being rotatably supported 100

and bearing pictorial representations, means carried by said cylinder responsive to heat waves from the lamp for rotating said cylinder, and a translucent shade outside said cylinder to expose the projected pictorial representations from the cylinder, said shade being angled in its cross-section, to present a polygonal shape, having concavo-convex sides, for the purpose of creating the effect of modified form and motion to the representations projected thereon.

2. The combination with a lamp of a transparent, hollow cylinder surrounding said lamp, said cylinder being rotatably supported and bearing pictorial representations, means carried by said cylinder responsive to heat waves from the lamp for rotating said cylinder, and a translucent shade outside said cylinder to expose the projected pictorial representations from the cylinder, said shade being angled in its cross-section to present a polygonal shape, having concavo-convex sides and rounded points of intersection, for the purpose of creating the effect of modified form and motion to the representations projected thereon.

New York, N. Y., August 10th, 1931.

WILLIAM A. ADAMS.
